CLAIM

The ornamental design for a mask, as shown and described.

DESCRIPTION

FIG. 1 is a front view of a mask;

FIG. 2 is a rear view thereof;

FIG. 3 is a right-side elevational view, the left side being a mirror image, with the strap in a position of use thereof; and, FIG. 4 is a rear perspective view thereof with the strap in a position of use.

The grayed out features surrounded in broken lines represent portions of the mask that form no part of the claimed design.

1 Claim, 4 Drawing Sheets
